Primary Examiner — David G Muller*Assistant Examiner* — Nathan M Johnston(74) *Attorney, Agent, or Firm* — Honigman LLP; Kelly T. Murphy; Jonathan P. O'Brien(57) **CLAIM**

The ornamental design for a base mount support, as shown and described.

DESCRIPTION

FIG. 1 is a front perspective view of a base mount support, showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The dashed lines in the drawing views depict portions of the design that form no part of the claim.

1 Claim, 4 Drawing Sheets(56)
